UNITED STATES PATENT OFFICE.

ANTRANIG CHAKARIAN, OF PHILADELPHIA, PENNSYLVANIA.

SHOE HEEL.

Application filed October 21, 1925. Serial No. 63,963.

This invention relates to shoe heels, and an object of the invention is to provide a shoe heel construction by means of which any unskilled person may remove a worn heel and replace it with a new one, may reverse the position of the heels in case the heel becomes worn excessively on one side.

More specifically, the invention comprehends the provision of a heel lift having a depending flange from which a pin projects, and also a hinged member having a plurality of pins thereon, the said pins being adapted to engage in suitable recess in a removable heel portion which may be made either of

leather, rubber, or analogous material.

Other objects of the invention will appear in the following detail description, and in the accompanying drawings wherein:

20 Figure 1 is a longitudinal section through the improved heel showing it in closed position.

Figure 2 is a plan view of the heel lift with the removable heel section removed.

25 Figure 3 is a detail view of the removable heel section.

Figure 4 is a cross section through the heel.

26 Figure 5 is a side elevation of the completed heel.

Figure 6 is a view showing the application of the hinge.

Referring more particularly to the drawings, the improved shoe heel structure comprises a lift 1 which is attached to the sole of a shoe in the usual manner, such as by nails, screws, or the like. A depending flange 2 is formed upon the lift 1 and extends about the curved sides of the lift, leaving the forward end of the heel free, so as to permit the insertion of the removable heel portion 3 in the recess formed by the flange 2. The removable heel section 3 has an overhanging flange 4 which overhangs the edges of the flange 2 and also overhangs the edges of the hinged locking member 5 when the latter is in its closed normal position.

The member 5 is connected by means of spring hinges 6 of any approved construction, with the lift 1, and it has a plurality of pins 7 thereon for projecting from its inner surface, which pins are adapted to seat in recesses 8 in the removable heel 4. The removable heel 4 is provided with a recess 9 at the center of its rear portion which receives a pin 10 that projects through the flange 2, and thus when the removable heel is in position and a hinged locking member 5 is closed, the pins 7 and 10 will engage in the recesses 8 and 9 and lock the heel 4 to the lift 1.

It is to be understood, that the heel 4 may be of leather, rubber, or the like.

From the foregoing description, taken in connection with the accompanying drawings, it will be apparent that the removable heel 4 may be removed or replaced or changed by any unskilled person without requiring the services of a skilled shoemaker or shoe repairer, and that the heels may be 70 changed at any time or any place desired, without inconvenience, and furthermore, that the removable heel sections 4 may be purchased in a store at a relatively low cost.

It is, of course, to be understood, that the 75 invention may be constructed in various other manners, and the parts associated in different relations, and therefore, I do not desire to be limited in any manner, except as set forth in the claim hereunto appended.

What I claim is:

In a shoe heel, a lift, a flange about the side edges of said lift and forming a recess, a removable heel in said recess and having an annular flange overhanging the edges of 85 said first named flange, a locking pin carried by said flange for engagement in the removable heel section, and a locking member hinged to the front edge of the lift and provided with a plurality of pins for engagement in the removable heel section to lock it in place.

In testimony whereof I affix my signature.

ANTRANIG CHAKARIAN.
